UNITED STATES PATENT OFFICE.

SALVATORE ANSALDO, OF BROOKLYN, NEW YORK.

METHOD OF MAKING SHOES.

Application filed April 9, 1927. Serial No. 182,464.

This invention is concerned with the provision of a novel shoe and a novel method of making same, particularly with an improved shoe of the McKay process.

5 An object of the invention is to provide a shoe of this character which will be lighter in weight and considerably more flexible than the conventional McKay shoe.

Another object of the invention is to provide 10 a method of making the shoe which represents a simplification and saving in time and labor over the method now in use.

Other objects of the invention are to provide 15 a shoe of simple, practical construction which will be attractive in appearance, comfortable to wear and well suited to the requirements of economical manufacture.

With the above noted and other objects in view, the invention consists in certain 20 novel features of construction and combinations and arrangements of parts, as will be more fully hereinafter set forth and pointed out in the claim. The invention may be more fully understood from the following 25 description in connection with the accompanying drawings, wherein:

Fig. 1 is a plan view of the under face of an insole showing the heel portion of the insole body broken away to expose the canvas upper surface.

30 Fig. 2 is a bottom plan view showing the shoe upper attached to the last, with the counter and rear portion of the vamp tacked down in the usual manner, and the forward portion of the vamp pasted down to the insole and held by tacks while the paste is setting.

Fig. 3 is a view similar to Fig. 2, but showing the last mentioned tacks removed 40 and a canvas member pasted or cemented over the edges of the counter.

Fig. 4 is a perspective view of an insole liner.

Fig. 5 is a longitudinal sectional view 45 through a completed shoe.

The novel construction of the shoe will fully appear from a general description of the method by which it is made. In the drawings, the last does not appear, but it will be understood that Figs. 2 and 3 show the position of the shoe on the last. Here, the insole 10 provided with a canvas covering 11 on its upper face is laid with its canvas face against the last. The shoe upper 55 including the vamp 12 and counter 13 is then

pulled around the last, and the counter edges tacked down to the insole as at 14 in the usual manner. Preferably the rear portion of the vamp 12 is also secured by tacks 14.

To avoid the use of tacks at the forward portion of the vamp and adjacent the ball of a wearer's foot, I apply any suitable type of cement or paste 15 to the under face of the forward portion of the insole 11, and the vamp 12 with its lining 12^a is pulled over 60 the last and pressed against the cement bearing face of the insole, thereby being secured without the use of tacks in the finished shoe. The tacks 16 of Fig. 2 are simply used to hold the vamp portion tightly stretched over 65 the last while the cement is setting.

After the cement has set, the tacks 16 are removed and a suitably shaped piece of canvas 17 pasted against the bottom of the shoe covering the forward portion of the vamp 73 and its lining. Subsequently the usual shank stiffener 19 may be applied to the under face of the insole, and the outer sole 20 and heel 21 attached. I may resort to a novel expedient in attaching the heel, which 78 consists in the use of an insole liner 22 longitudinally slit or divided on its rear end to provide a pair of separable flap portions 23 and 24. The flap 24 may be lifted while driving home the heel retaining tacks 25 and 83 then subsequently pasted down to cover the heads of the tacks. In Fig. 5 the dotted lines indicate the position of the lifted flap prior to its pasting down. The sole 20 is 88 sewed to the shoe in the usual manner.

The canvas on the upper face of the insole serves a two-fold purpose. In the first place it promotes economy by permitting the use of a very thin leather insole, the canvas preventing such thin insole from stretching 95 or spreading. In the second place, it affords a very firm anchorage for the shank, preventing the shank from sliding. In the ordinary construction, the shank in use, slides over the leather face of the insole and causes objectionable squeaking of the shoe.

Due to the absence of tacks in the forward portion of the shoe which is subject to the greatest number of bending strains as the wearer flexes her foot when walking, this 105 portion of the shoe will be extremely flexible, conforming to the flexures of the foot and rendering the shoe extremely comfortable in use. The elimination of the tacks also materially reduces the weight of the 110

shoe at this point, and there is no danger of any of the tacks working through the insole and injuring or chafing the foot.

Obviously various changes and alterations might be made both in the method and in the shoe without departing from the invention. Hence I do not wish to limit myself to the details set forth, but shall consider myself at liberty to make such changes 10 and alterations as fairly fall within the spirit and scope of the appended claim.

I claim:

A method of making shoes, which includes the step of applying adhesive to the 15 under face of a shoe insole, pulling the edges of a vamp and its lining over the adhesive

coated face of the insole while the insole and vamp are arranged on a last, pressing said edges against the insole to cause them to adhere thereto, temporarily tacking the 20 vamp and lining edges in tautly stretched condition while the adhesive is drying, removing the tacks and applying a second adhesive coat over the exposed portion of the insole and the pulled over edges of the vamp and lining, placing a piece of canvas against the under face of the insole and the turned over edges of the vamp and lining to conceal said edges, and after the cement has set 25 to hold the canvas, applying the outer sole 30 and heel.

SALVATORE ANSALDO.
